Des. 234,911
Patented Apr. 15, 1975

234,911

COMBINED BOTTLE AND CLOSURE THEREFOR OR THE LIKE

Peter P. Stevens, Jr., P.O. Box 95,
Point Reyes Station, Calif. 94956

Filed Mar. 21, 1973, Ser. No. 343,292

Term of patent 14 years

Int. Cl. D9—01

U.S. Cl. D9—117

Fig. 3

Fig. 1

Fig. 2

Fig. 4

Fig. 5

Fig. 6

Fig. 7

FIG. 1 is an elevational view of a combined bottle and closure therefor or the like showing my new design, the opposite side being the same in appearance as the side shown;

FIG. 2 is an elevational view looking from the right of FIG. 1, the opposite side being the same in appearance as the side shown;

FIG. 3 is a top plan view;

FIG. 4 is a bottom plan view;

FIG. 5 is a horizontal section taken in a plane indicated by line 5—5 in FIG. 1;

FIG. 6 is a horizontal section taken in a plane indicated by line 6—6 in FIG. 1; and

FIG. 7 is a fragmentary vertical longitudinal sectional view taken in a plane indicated by line 7—7 in FIG. 1.

I claim:

The ornamental design for a combined bottle and closure therefor or the like, substantially as shown and described.
